UNITED STATES PATENT OFFICE.

AUGUST TAPPE AND CHARLES TAPPE, OF BLOOMINGTON, ILLINOIS.

TOBACCO-PIPE.

SPECIFICATION forming part of Letters Patent No. 331,569, dated December 1, 1885.

Application filed June 30, 1884. Serial No. 136,415. (No model.)

To all whom it may concern:

Be it known that we, AUGUST TAPPE and CHARLES TAPPE, of Bloomington, in the county of McLean and State of Illinois, have 5 invented a new and useful Improvement in Tobacco-Pipes and Cigar-Holders, of which the following a full, clear, and exact description.

This invention relates to the novel construction and peculiar arrangement of the several parts composing a pipe for smoking tobacco and other substances, so as to impede the passage of the smoke through it, to collect and hold the nicotine, and to cool, purify, and 15 render the smoke more agreeable and less injurious.

Reference is to be had to the accompanying drawings, forming part of this specification, in which similar letters of reference indicate 20 corresponding parts in both the figures.

Figure 1 represents a central longitudinal section of a tobacco-pipe having our improvements applied thereto; Fig. 2, a cross-section through line $x-x$ of Fig. 1.

25 Fig. 1 in the accompanying drawings represents a central longitudinal section of a pipe, consisting of a stem of the usual curved form, a cap, B, body A, intermediate lower section, D, and bowl E.

30 Within the body A are arranged the several devices through which the smoke from the bowl is to pass to be purified of the nicotine and cooled before reaching the mouth. To the lower end of this body A, and between it and the bowl E, is placed an intermediate detachable section, D, secured to the lower end of the central section, A, by a screw-thread, b, and attached to the bowl E by a tapered neck and screw-thread, d, which neck terminates at a 35 small draft-recess, e, into which the smoke from the bowl first passes. The cap B closes the upper end of the central section, A, and to which a stem or mouth-piece of the usual curved form is secured by means of a screw-thread 40 thereon in the usual manner. This mouth-piece extends through the cap B and projects downward centrally a short distance into the upper end of the body A. Secured centrally to this intermediate lower section, D, is a 45 small tube, F, which extends upward and

terminates within a short distance of the upper closed end of a larger return-tube, H, leaving an enlarged recess therein, as represented in Fig. 1. To this central tube, F, are fitted two diaphragms, G, G', having perforations g, 55 through which the smoke is to pass from the tube F. Between these perforated diaphragms G, G', and to the interior surface of the return-tube H, is fitted a spiral, I, to retard the smoke through and around it in its course between 60 the diaphragms G, G'. The return-tube H, with its spiral I, is supported by means of the diaphragms G, G' centrally and about midway within the body A. By placing this return-tube H midway in the body A the spaces or 65 recesses between the upper and lower ends thereof are formed as shown in Fig. 1, and this return-tube H being somewhat smaller in diameter than the interior diameter of the body A, a narrow annular passage-way, h, is 70 formed between them to connect the upper and lower spaces or recesses, as represented. By thus constructing a pipe for smoking tobacco in sections economy of material and facility of assembling the several parts are attained. 75 The several pieces composing this pipe having been properly fitted, they are assembled as follows: The return-tube H is first mounted upon the smaller tube F, and supported thereon by the diaphragms G, G'. The tube F is then 80 screwed into the lower section, D, and section D screwed into the bowl E. The body A is then placed over the return tube H and screwed to section D at b. The cap B is secured to the upper end of the body A, and the stem or 85 mouth-piece screwed to the cap B, thus completing the pipe, as represented in Fig. 1, in a merchantable condition. The course of the smoke through the various channels in this pipe may be described as follows: From the 90 bowl E the smoke enters, first, the draft-recess e; thence upward through the small tube F; thence drawn downward through the perforations g in the upper diaphragm, G; thence over and through the spiral I, and through the lower diaphragm, G', entering and expanding into the space or enlarged recess below the tube H in the intermediate section, D; thence upward in a thin annular column between the tube H and interior surface of the body A, to 100

enter and again expand in the upper space or recess in the body A above the tube H, and thence through the stem into the mouth. By the time the smoke shall have traversed these 5 various channels from the bowl E to the stem or mouth-piece it is materially cooled, and the nicotine will precipitate and become a deposit in the lower space or recess in section D, from which it can be readily removed at pleasure.

10 Having thus described our invention, we claim as new and desire to secure by Letters Patent—

As an improved article of manufacture, a

pipe for smoking tobacco and other substances, constructed and arranged substantially as described, consisting of a bowl, E, and stem or mouth-piece, body A, intermediate detachable section, D, tube F, and return-tube H, having a spiral, I, therein inclosed between two perforated diaphragms, as set forth. 15

AUGUST TAPPE.
CHARLES TAPPE.
